UNITED STATES PATENT OFFICE.

MORRIS SCHWERIN, OF NEWARK, NEW JERSEY.

BAG OR SATCHEL.

SPECIFICATION forming part of Letters Patent No. 325,978, dated September 8, 1885.

Application filed June 10, 1885. (Model.)

To all whom it may concern:

Be it known that I, MORRIS SCHWERIN, of Newark, in the county of Essex and State of New Jersey, have invented certain new and useful Improvements in Bags and Satchels; and I do hereby declare the following to be a full, clear, and exact description of the invention, such as will enable others skilled in the art to which it pertains to make and use it, reference being had to the accompanying drawings, which form part of this specification.

My invention relates to an improvement in traveling-bags; and it consists in a frame having an overlapping flange upon its outer side for the purpose of forming both a protection and a guide for the edge of the material out of which the bag is made, all of which will be more fully described hereinafter.

The object of my invention is to provide a frame to which the bag can be stitched, and to so construct the frame that it will hide the edge of the material out of which the bag is made, and thus enable unskilled and inexperienced laborers to turn out elegant work.

Figure 1 is a side elevation of a bag embodying my invention. Figs. 2 and 3 are vertical sections of the same.

A represents the frame-work of a bag of any kind, and which is provided with a series of perforations, B, extending in a line along the frame at that point where the bag is to be stitched to the frame. These holes will be punched any desired distance apart, and as the stitches can only be made of a length equal to the distance between the holes, the stitches must always be made uniform. These holes serve as a guide to the workmen doing the stitching, and hence inexperienced workmen can do as neat work as the most experienced.

In order to guide the edge of the material, as well as to protect and hide it, there is an overlapping outwardly-projecting flange, F, formed upon the upper edge of the frame, and which flange is just wide enough to extend over the edge of the material, as shown. This flange serves as a guide to enable the workmen to push the material into its proper place without exercising any special diligence or care. The edge of the material, fitting tightly under this flange, is hidden completely from view and an elegant finish is given to the bag. It is immaterial how this flange is formed

upon the frame. As here shown, the frame is made in two parts, and the outer piece, D, is made to overlap the inner piece for the purpose of forming this flange. If desired, the frame may be formed in a single piece, and have the flange formed upon it while the metal is being rolled.

Heretofore this class of frames have had the locks secured on their inner sides, but by the construction here shown the lock can be attached entirely to the outer side of the frame, so as to leave the inner side of the frame free, and thus give the bag a nicer appearance and finish. The holes in the frame and hasp make the sewing-in of the bag easy, as the stitches pass through the holes and must always be uniform. The sewing can be done by inexperienced workmen, because they can only put the stitches where they belong. The flange on the frame protects the edge of the leather from being bent over, and at the same time guides the workman in getting his work straight and uniform, as he cannot push the edge of the leather any farther than the flange. The frame here shown can be made cheaper and much stronger than the frame originally used. By placing the lock entirely outside of the frame, as here shown, should it get out of order at any time the parts can be readily gotten at without having to break the bag open.

Having thus described my invention, I claim—

1. A bag-frame provided with a series of perforations through which the material which forms the bag is sewed to the frame, and with a projecting flange around its outer edges to come flush with and hide the edges of the material, substantially as shown.

2. In a bag-frame, the combination of the frame A, provided with a series of perforations, B, with the separate and independent pieces D, which are secured to the frame and have their outer edges to form the flanges F, to come flush with and hide the edges of the material out of which the bag is formed, substantially as specified.

In testimony whereof I affix my signature in presence of two witnesses.

MORRIS SCHWERIN.
